UNITED STATES PATENT OFFICE

JOHN S. TURNBULL, OF NEW YORK, N. Y.

AUTOMATIC DOOR-FASTENING MECHANISM

Application filed November 26, 1923, Serial No. 676,947. Renewed June 24, 1930.

Where a pair of doors are employed to close a doorway, one manner of fastening the doors closed is to fasten one of the doors closed, as by bolting it to a portion of the door casing, and then to lock the other door, as by the ordinary hasp and padlock to the first door.

The present invention has for its object to provide means operated automatically by movement of the second door to and from closed position to fasten and unfasten the first door to and from the door casing or other suitable part of the building. It is further contemplated that the doors may be so interconnected that movement of one door moves the other, the interconnection being such that the one door moves to substantially closed position first whereupon it is fastened by the later closing of the second door and is first unfastened and then opened by opening movement imparted to the second door.

For a more complete understanding of the invention reference may be had to the accompanying drawings in which

Figure 1 is a somewhat diagrammatic plan illustrating the invention as applied to a pair of doors hinged to opposite sides of a door casing and interconnected for joint actuation.

Figure 2 is a fragmentary section through adjacent portions of the doors and illustrating in solid lines the completely closed positions of the doors and in the dotted lines the positions of the parts when the second door is partly open.

Figure 3 is a fragmentary elevation showing the doors closed.

Figure 4 is a detail section showing the positions of the lock mechanism corresponding to certain positions of the second door.

Figure 5 is a view somewhat similar to Figure 2 illustrating a slight modification.

Referring to these figures, 1 indicates a pair of door posts defining opposite sides of a doorway. To these posts are hinged a pair of doors indicated at 2 and 3 which close together to close the doorway. In order that motion imparted to one door may also move the other, they may be connected by means such as shown in Figure 1 comprising a

bracket 4 fixed to one of the doors, as the door 2, and having an arm 5 extending therefrom, a bracket 6 fixed to the door 3, and a link 7 pivotally connecting the arm 5 with the bracket 6. With this construction relative velocities of the two doors in their opening and closing movements vary during different portions of such movements. As shown the door 2 starts to close with a relatively rapid motion while the door 3 is closing with a relatively slow motion. As the door 2 approaches its closed position its motion becomes relatively slow, while the velocity of the door 3 is relatively great. The door 2 is thus substantially closed while the door 3 is yet somewhat open. A batten strip 8 applied to the outer edge of the door 3 will then overlap the joint between the doors without interfering in any way with the motion of either. These doors may be locked in closed position, therefore, by fastening the door 2 to any suitable portion of the building, as for example, a portion of the door casing, when it is substantially fully closed, then completing the closing of the door 3 so that the strip 8 overlies the joint between the doors, as shown in full lines in Figure 2, and then locking the door 3 in any suitable manner to the door 2 as by means of the ordinary hasp and padlock.

According to the present invention means are provided for fastening the door 2 to the casing when it is substantially in its fully closed position by movement of the door 3 to fully closed position and by which unfastening of the door 2 is effected during the initial opening of the door 3 before the door 2 has substantially started to open. One means of accomplishing this comprises a latch bolt 10 carried by a casing 11 fixed to the door 2, the latch bolt 10 being projectable beyond the edge of the door into a suitable socket 12 in the door casing as shown more particularly in Figures 3 and 4. The bolt 10 at its opposite end is provided with a slot 13 in which rides a crank arm 14 at one end of a rock shaft 15. This rock shaft is supported for rotation in a bracket member 16 made fast to the door 2 and the opposite end of the rock shaft 15 has a crank arm 17 which pro-

jects beyond the free end of the door 2. The bolt 10 is normally held in retracted position, for this purpose a spring 18 being shown housed within the casing 11. Also for the same purpose a torsion spring 19 may be employed acting on the rock shaft 15 and supported by the bracket 16. Either of the springs 18 or 19 may be employed alone, if desired, or both may be used in conjunction. When the bolt 10 is in retracted position the crank arm 17 projects outwardly from the door 2, as shown in Figure 1 and in dotted lines in Figures 2 and 4. It is then in position to be struck by the inner face of the door 3 after the door 2 has been substantially closed and the door 3 has still some distance to swing in order to bring it to closed position. This last portion of the closing movement of the door 3, acting on the arm 17, rocks the shaft 15 so that the bolt 10 is projected into the socket 12 so that the door 2 is fastened closed. When the door 3 opens the springs for retracting the latch bolt 10 are permitted to act since the crank arm 17 may take its former position extending outwardly of the door 2, so that during the initial opening movement of the door 3 the door 2 is unlatched, and on further swinging movement of the door 3 the door 2 is opened. It may be desirable to effect a positive release of the latch 10 on initial opening of the door 3. If this is desired a loop 20 may be made fast to the inner face of the door 3 so positioned relative to the end of the crank arm 17 that as the door contacts therewith, the end of this crank arm passes within this loop so that in fully closed position of both doors the end 17 is fully engaged therein. When the door 3 is then given its initial opening movement, the arm 17 is caught by the loop 20 and forced towards latch-releasing position at which time the loop 20 slips over the end of the portion 17 so that there is no interference with the proper movement of the doors in either their opening or closing movements.

In case the relative travel of the loop and the member 17 is normally insufficient to effect a positive engagement therebetween when the doors are closed and yet permit their release when the doors start to open, the crank arm 15 may be mounted in an inclined position on the door 2 in the manner shown in Figure 5 so that as the rock shaft turns the portion 17 thereof is given a bodily movement transverse to the plane of the closed doors. By this means a relative motion between the loop and the arm 17 of any desired amplitude may be effected in order to insure the proper coaction of these members.

Having thus described certain embodiments of this invention, it should be evident to those skilled in the art that many changes and modifications might be made therein

without departing from its spirit or scope.

I claim:

1. A latching device for one of a pair of doors together closing a doorway, which comprises a latch mechanism carried by one of said doors, and means operated by the last portion of the closing movement of the other door to positively latch said mechanism and the first portion of the opening movement of said other door to positively release said mechanism.

2. In combination with a plurality of doors, a latch carried by one of said doors, an operating member for said latch extending into the path of motion of the other door to be actuated thereby, and means carried by the other door for engaging said member to release said latch on the reverse motion of said other door.

3. In combination with a pair of doors hinged at opposite sides of a doorway and movable together to close said doorway, a latch bolt carried by one of said doors and engageable with a fixed element for fastening said door closed, a rock shaft carried by said door and having a portion operatively engaging said bolt to project and retract the same by rocking thereof, means normally holding said bolt in retracted position, and an element projecting from said rock shaft into the path of motion of the other of said doors as it nears closed position and movable by said other door as it closes to rock said shaft to bolt-projecting position.

4. In combination with a pair of doors hinged at opposite sides of a doorway and movable together to close said doorway, a latch bolt carried by one of said doors and engageable with a fixed element for fastening said door closed, a rock shaft operatively related to said bolt to project and retract the same by rocking thereof, means normally holding said bolt in retracted position, an element projecting from said rock shaft into the path of motion of the other of said doors as it nears closed position and movable by said other door as it closes to rock said shaft to bolt-projecting position, and means on said other door for engaging said element as said other door starts to open to rock said shaft to bolt-retracted position.

In testimony whereof I have affixed my signature.

JOHN S. TURNBULL.
